UNITED STATES PATENT OFFICE.

GEORGE LOUIS PLATTS, OF DETROIT, MICHIGAN

TRAY-CHAIR.

1,383,020.

Specification of Letters Patent. Patented June 28, 1921.

Application filed September 9, 1920. Serial No. 409,230.

To all whom it may concern:

Be it known that I, GEORGE LOUIS PLATTS, a citizen of the United States, residing at Detroit, in the county of Wayne and State 5 of Michigan, have invented certain new and useful Improvements in Tray-Chairs, of which the following is a specification, reference being had to the accompanying drawings.

10 This invention relates to tray chairs for use in restaurants.

An important object of the invention is to provide a chair having means whereby a serving tray may be detachably secured 15 thereto. In self-serving lunch rooms and in lunch rooms of the cafeteria type, the food is removed from the counter by the patron and taken to a seat. In some of these institutions chairs are provided, having at the forward end of the arm an enlarged portion which serves as a support 20 for the dishes containing food. In these institutions it is necessary for the patron to secure the dishes and place them upon 25 such enlarged portion. Generally no tray is provided, necessitating the carrying of the dishes in the hand, ordinarily requiring two or three trips to remove a light lunch from the counter to the seat. Where a tray 30 is provided there is no provision for the disposal of the tray except to return the tray to the counter, necessitating an extra trip on the part of the patron. In other institutions, where tables are provided, the 35 food is carried by the patron, either by hand or upon a tray to the table. The use of tables, is, however, space consuming and is only resorted to, to provide comfort for the patrons. It is impossible to make the enlargement upon the ends of the arms of the 40 chairs previously mentioned sufficiently large to accommodate a large number of dishes, because of the fact that these enlargements being permanently in position consume constantly so much space. In order to remove 45 these difficulties, I have provided a chair having combined therewith means for attaching a tray thereto, the tray being provided with means for coacting with and 50 engaging the means carried by the chair in such a manner that accidental displacement of the tray is practically impossible. This construction renders it possible for the patron to be supplied with a tray upon 55 which to collect and carry such articles as he may desire, and, subsequently, to use the

tray as a table while eating, thus avoiding the extra trip ordinarily necessary. This construction has a further advantage in that the tray may be removed by employees, together with the dirty dishes carried thereby in a convenient manner.

A further object of the invention is to provide in a device of this character means whereby the tray may be removably attached to the chair by a straight line horizontal movement of the tray toward the chair, and means whereby the tray is supported with its upper surface substantially co-planar with the upper surface of the arm 60 of the chair.

Other objects and advantages of the invention will become apparent throughout the course of the following description.

In the accompanying drawings, wherein 75 for the purpose of illustration is shown a preferred embodiment of my invention and wherein like reference characters designate like parts throughout:

Figure 1 is a side elevation of a tray chair 80 constructed in accordance with my invention.

Fig. 2 is a plan view thereof.

Fig. 3 is a side elevation of the bracket employed for supporting the tray.

Fig. 4 is a section on the line 4-4 of 85 Fig. 3.

Fig. 5 is a plan view of the bracket.

Fig. 6 is a fragmentary bottom plan view of the tray showing the guides attached thereto, and

Fig. 7 is a fragmentary side elevation of 90 the tray.

Referring now more particularly to the drawings the numeral 10 indicates a chair and the numeral 11 the arm thereof. This 95 arm has secured thereto a bracket 12.

The bracket, 12, embodies at its upper end horizontally extending portions 13 provided at the ends thereof with vertically extending members 14 which embody forwardly extending lugs 15 spaced above and extending over the horizontal portions 13. The bracket is provided centrally at the upper end thereof with a horizontal tongue extending forwardly therefrom, as indicated at 16. The 100 bracket has extending forwardly and upwardly from the forward face thereof a suitably braced arm 17 provided at its upper end with a horizontally disposed preferably circular flat head 18 coplanar with the 110 tongue 16.

A tray T is provided, having in its lower

surface a groove 19 formed in the present instance by spaced tracks 20 secured to the under surface of the tray, as by riveting, as at 20^a. The conformation of these tracks is such that the portions thereof are spaced from the bottom of the tray at each side of the groove forming a slideway for the head 18 and a receptacle for the tongue 16. This groove and the tracks 20 extend to one marginal edge of the tray. The tray is, as in the usual construction, provided with an upstanding marginal flange F and the edge thereof to which the tracks 20 extend is provided with spaced openings O, spaced apart a distance equal to the distance between the lugs 15.

In the use of my device the patron employs the tray to secure the desired viands and returns with the tray, engaging the slot 20 of the under surface thereof with the head rest and moves the tray toward the chair with a straight line movement. When in proper position the tongue 16 engages between the outer end of the tracks and the bottom of the tray and the bottom of the tray at the sides of the tongue 16 is supported by the horizontal portions 13. The lugs 15 likewise engage in the openings O, preventing upward displacement of the tray. It will be obvious that the portions 13 and tongue will combine to prevent downward displacement of the tray at this end and that displacement in any direction except that opposed to the direction of movement in applying the tray at the outer end of the tray is prevented by the fact that the arm 17 has a sliding fit in the groove 19 and the head 18 is held between the tracks 20 and the bottom of the tray. I do not wish to be understood as limiting myself to the use of the above described device in self-serving restaurants alone, as it will be readily understood that the device could likewise be employed in restaurants utilizing waiters.

It will further be obvious that my device is particularly well adapted for use by reason of the fact that it eliminates unnecessary labor and permits of serving a maximum number of patrons in the given space, and it will likewise be obvious that the construction of the same as hereinbefore set forth is capable of some change without departing from the spirit of my invention. I accordingly do not limit myself to the specific construction as hereinbefore set forth, except as so limited by the subjoined claims.

Having now described my invention, what I claim is:

1. The combination with a serving tray and a chair, of means for detachably securing the serving tray to the chair embodying a support secured to the chair and provided at its upper end with means adapted to engage a side of the tray to prevent vertical displacement thereof and means extending

forwardly from the support for engaging the under surface of the tray to support the same.

2. The combination with a serving tray and a chair, of means for detachably securing the serving tray to the chair embodying a substantially vertical support secured to the chair and provided at its upper end with a flattened portion adapted to receive the under surface of one edge of the tray and prevent downward displacement thereof, means carried by said support and engaging the edge of said tray to prevent upward displacement thereof, and means extending forwardly from the support and engaging the under surface of the tray to support the same.

3. The combination with a serving tray and a chair, of means for detachably securing the serving tray to the chair embodying a substantially vertical support secured to the chair and provided at its upper end with a flattened portion adapted to receive the under surface of one edge of the tray and prevent downward displacement thereof, means carried by said support and engaging the edge thereof to prevent upward displacement thereof, and means extending forwardly from the support and engaging the under surface of the tray to support the same, said last named means likewise preventing transverse shifting of the tray.

4. The combination with a chair provided with a substantially vertical support having at its upper end oppositely extending horizontal portions, a forwardly extending tongue formed on said support, an arm extending forwardly from said support and provided with a head, and portions extending upwardly from said oppositely extending arms, and provided with forwardly extending lugs, of a tray provided upon the under surface thereof with spaced tracks affording therebetween a groove to slidably receive said arm, said tracks having their adjacent edges spaced from the bottom of the tray to afford a space for the reception of said head and tongue, and openings formed in the side of said tray adapted to receive said, forwardly extending lugs.

5. The combination with a serving tray and a chair, of means for detachably securing the serving tray to the chair embodying a support secured to the chair and provided with means adapted to engage a side of the tray to prevent vertical displacement thereof and means for engaging the under surface of the tray to support the same, said tray being rotatable upon the last named means when out of engagement with the first named means.

6. The combination with a chair, of a tray and means for detachably securing the tray to the chair by horizontal movement embodying a member having interlocking en-

gagement with the bottom of the tray preventing transverse movement of said tray but permitting rotary movement thereof and means for engaging the tray to prevent rotation thereof.

7. The combination with a serving tray and a chair, of means for detachably securing the serving tray to the chair, embodying a support secured to the chair and provided

10 at its upper end with means adapted to en-

gage the side of the tray to prevent vertical displacement thereof and means extending forwardly from the support for engaging the under surface of the tray to support the same, said tray being rotatable upon the last 15 named means when out of engagement with said first named means.

In testimony whereof I hereunto affix my signature.

GEORGE LOUIS PLATTS.
